BEDSIDE CLOCK SHELF

Filed June 3, 1949

FIG. 1.

UNITED STATES PATENT OFFICE

2,538,449

BEDSIDE CLOCK SHELF

Chester E. Freshwater, Follansbee, W. Va.

Application June 3, 1949, Serial No. 96,860

3 Claims. (Cl. 248—115)

1

This invention relates to a bedside clock shelf and more particularly to an adjustable clock shelf for attachment to a bed or the like.

It is an object of this invention to provide a clock supporting device of the kind to be more particularly described hereinafter formed for clamping engagement on the horizontal board running from the head to the foot of the bed. The clock is to be positioned on the bed in a manner whereby the dial can be easily read and the alarm turned off.

Another object of this invention is to provide a clock shelf of this kind made of metal, plastic or other suitable material particularly designed to fit standard size beds and alarm clocks.

A further object of this invention is to provide a bedside clock shelf, the use of which will obviate the requirement of small stands or bedside tables usually used for this purpose thus saving floor space and supporting the clock in a position where it may be readily reached by a person reclining in the bed.

With the above and other objects in view, my invention consists in the novel structure, arrangement and combination of details of construction, as set forth in the specification and drawings and more particularly in the appended claims.

In the drawings:

Figure 1 is a side elevation of a bedside clock shelf, constructed according to an embodiment of this invention, secured on a longitudinal bed rail.

Figure 2 is a side elevation of the clock shelf, removed from the bed.

Figure 3 is a top plan view.

Figure 4 is a longitudinal section, taken on the line 4—4 of Figure 3.

Figure 5 is a transverse section, taken on the line 5—5 of Figure 3.

Figure 6 is a perspective view of a rubber cushion used on the clock engaging clamping prongs.

Referring to the drawings, the numeral 10 designates generally a bedside shelf for supporting an alarm clock or the like adjacent a bed, as on one longitudinal bed rail 11 of the bed 12. The shelf 10 may be positioned at any selected point along the length of the bed as adjacent the head 14 or near a pillow supported on the bed. The design, construction and disposition of the shelf 10 permits the unobstructed movement of a person on to or off from the bed while securely supporting the clock 15 thereon.

The clock shelf 10 is formed of a longitudinally

2

extending flat, horizontal, supporting base or base member 16, having a clamp 17 on one end and a second clamp 18 on the other end. The base plate 16 is formed with a pair of transversely spaced apart bolt receiving openings 19 adjacent one end and a longitudinally extending slot 20 at the transverse median adjacent the other end.

A pair of vertically extending clamping jaw members 21 and 22 are fixed to or formed on the opposite ends of the outer transverse edge of the base member 16 and, preferably, a resilient cushion or rubber sleeve 24 is engaged on each of the prongs 21 and 22 for cushioned clamping engagement with the clock 15 to be clamped on the base 16.

The upstanding prongs 21 and 22 constitute the fixed jaw member 25 on the outer end of the base which forms one of the jaw members of the outer clamp 18. A slideable clamping jaw member 26 is slidably supported on the outer end of the base 16 and is formed with a flat plate 27 slideable on the upper side of the base 16 having a longitudinally extending slot 28 extending along the center thereof. A bolt 29 is engaged through the slots 20 and 28 and a winged nut 30 engaging on the screw 29 secures the clamping jaw 26 on the base 16. A pair of transversely spaced apart, upwardly extending prongs 31 and 32 on the outer end of the plate 27 constitute the clamping elements on the slideable jaw member 26 for clamping engagement with the clock 15 for clamping the clock against the fixed jaw members 21 and 22. A depending flange 34, on each longitudinal side edge of the plate 27, slidably engage the side edges of the base member 16 for guiding the clamping jaw 26 in its sliding movement on the base 16.

A downwardly and inwardly inclined side flange 35 is fixed to or formed on each side edge of the base member 16 and extends along the length thereof. The inner, vertical edge 36, on the inner end of each flange 35 constitutes the fixed clamping jaw for the clamp 17, depending from the plate 16. The slideable clamping jaw 37 of the clamp 17 is formed of a flat horizontal plate 38 underlying the inner end of the base member 16 between the flanges 35. The slideable jaw member 37 includes a depending clamping jaw 39 on the outer end of the plate 38 for engagement on the inner side of the bed rail 11. A pair of longitudinally extending slots 40 are formed on the plate 38 and a pair of bolts 41 are engaged through the openings 19 of the base plate and slots 40 for clamping the jaw member 37 in selected, adjusted, clamping position.

In the use and operation of the bedside clock shelf 10, the clamp 17 is engaged on the bed rail 11 and secured thereon. The clock 15 is then engaged between the jaw members 25 and 26 for securely clamping the clock 15 adjacent the head of the bed where it may be readily reached by a person reclining in the bed 12. In order to prevent the shelf 10 from scratching the bed 12, a felt, rubber or other suitable soft pad 42 is secured on the clamping jaws 39 and 36 for engagement with the bed rail 11.

I do not mean to confine myself to the exact details of construction herein disclosed, but claim all variations falling within the purview of the appended claims.

I claim:

1. A bedside clock shelf comprising a flat base member, a pair of depending longitudinal flanges on said base member, a bed rail engaging clamping elements slidably engageable on said base member for clamping a bed rail on one end of said flanges, an upwardly extending transverse clamping jaw on the outer end of said base member and a second slidably clamping member slidably on said base member for clamping an alarm clock against said transverse clamping jaw. 20

2. A bedside clock shelf comprising a flat horizontal base member, a pair of upwardly extend-

ing clamping prongs on one end of said base member, a clamping plate slidable on said base member, a pair of upwardly extending clamping prongs on said plate for clamping an alarm clock against the prongs on said base member, a clamping member slidable on the other end of said base member for clamping engagement with a bed rail and a fixed jaw member on said base member for cooperation with said latter clamping member. 10

3. A bedside clock shelf comprising a horizontal base member, a pair of upstanding clamping jaws on one end of said base member, a jaw member slidable on said base for clamping a clock against 15 said jaws, a pair of depending jaws on the other end of said base member and a second clamping jaw slidably engaging said base member for clamping a bed rail against said depending jaws.

CHESTER E. FRESHWATER.
